UNITED STATES PATENT OFFICE.

MAURICE F. GEER, OF IRONDEQUOIT, NEW YORK, ASSIGNOR TO GENERAL RAILWAY SIGNAL COMPANY, OF ROCHESTER, NEW YORK, A CORPORATION OF NEW YORK.

BEARING.

1,402,349.

Specification of Letters Patent. Patented Jan. 3, 1922.

Application filed December 27, 1919. Serial No. 347,684.

To all whom it may concern:

Be it known that I, MAURICE F. GEER, a citizen of the United States, and resident of the town of Irondequoit, in the county of Monroe and State of New York, have invented a new and useful Improvement in Bearings, of which the following is a specification.

This invention relates to a guard or protecting device for preventing oil leakage from high speed shaft bearings.

In one type of machine, specifically a power driven clothes washing machine, for which my invention is particularly adapted, a high speed shaft passes into a casing or housing enclosing the operating parts of the machine and containing a heavy gear oil or similar lubricant for these parts. In such a construction there is difficulty in preventing oil leakage from the bearing of this shaft, there being a considerable head of oil upon the bearing. It is found that an ordinary stuffing box construction will not prevent oil leakage from such bearings without being so tight as to produce excessive friction and wear on the shaft, and will not stand up in service without adjustment.

In accordance with my invention, I provide, as a substitute for the ordinary stuffing box, or as an additional protection to be used in connection therewith, a pump-like device which opposes the pressure of oil upon the bearing and prevents it leaking out, while at the same time the bearing is freely lubricated.

In describing the invention in detail, reference will be made to the accompanying drawings, in which like reference characters designate the corresponding parts in the several views, and in which

Figure 1 is a fragmentary view of a washing machine and operating mechanism therefor, to which I have illustrated my present invention applied, and

Fig. 2 is an enlarged horizontal section taken on the line 2-2 in Fig. 1, and shows the construction of one embodiment of my invention.

For the purpose of illustrating and explaining the construction and functions of my invention I have shown it applied to a clothes washing machine, but it should be understood that the invention may be used in connection with other machines under similar conditions by making appropriate

changes in mechanical details. This washing machine, shown in part in Fig. 1, comprises the usual legs 1 and framework 2, a tub 3 in which is supported the clothes cylinder or washing element (not shown) arranged so as to be operatively connected and disconnected with respect to a load-shaft 4 by a handle 5 and shifter mechanism in the well known way. The load-shaft 4 is driven by a pinion 6 which meshes with a gear sector 7 journaled on a suitable fixed bearing stud 8. The gear sector 7 is oscillated by a pitman or connecting rod 9, which is pivotally connected at one end to an arm of said gear sector, and is journaled at its other end on an eccentric pin 10 in a worm gear 11. The worm gear 11 is driven by an intermediate worm 12 fastened on a vertical drive shaft 13 supported in bearings 14. To the lower end of the drive shaft 13 is pinned a worm gear 15 which is driven by a high speed worm 16 on a worm shaft 17 which is driven by a suitable electric motor M. These parts are supported and enclosed in a unitary casing or housing S fastened by bolts 18 to the legs 1. This casing S is provided with a gear compartment C having a detachable bottom plate 19 (for the purpose of facilitating manufacture and assembly), in which is disposed the high speed worm 16 and the worm gear 15, this compartment C being in communication with the upper portion of the main casing S by means of a passage 20. The casing S is filled with a heavy gear oil or similar mobile lubricant to a level 90 approximately as indicated by the dash line A-A in Fig. 1.

Referring to Fig. 2, the high speed worm shaft 17 is journaled at one end in a detachable plug 21, and a thrust ball bearing 22 is interposed between this plug and a spacing sleeve 23 pinned to the shaft 17. The worm 16 is keyed to the shaft 17. The inner bearing for the worm shaft 17 comprises a sleeve 24 having an enlarged annular portion 25 constituting what is conveniently termed a pump casing. Between the bearing sleeve 24 and the worm 16 is a sleeve 26 pinned to the shaft 17 and provided with a double fin or ridge 27 spirally wound and constituting in effect the teeth of a duplex worm, these teeth being pitched opposite to the teeth of the worm 16 and fitting closely inside of the so-called pump casing 25. In the bearing sleeve 24 is an oil hole 28 com-

municating with the main portion of the gear compartment C through a channel 29. Outside of the bearing sleeve 24 I have shown a stuffing box of well known construction, comprising packing rings 30, a gland nut 31, and a lock nut 32.

In the type of construction above described, it will be evident that the inner bearing of the high speed worm shaft 17 is subjected to a considerable head of oil, and where a light body lubricant is used, difficulty has been found in obtaining a suitable stuffing box construction which will prevent oil leakage out of this bearing. In machines of this character leakage of oil is highly objectionable. Moreover, such machines do not ordinarily receive in service the care and attention required to make a stuffing box effective.

According to my invention leakage of oil out of the inner bearing for the high speed worm shaft 17 is prevented by opposing the oil pressure while said shaft is rotating, due to the pump action of the ridge 27 in the casing 25. The direction of rotation of the shaft 17 is indicated by arrow *a* in Fig. 2, and the ridge 27 is spirally wound so as to draw oil through passage 29 and hole 28 through the bearing sleeve 24, thereby providing free circulation of oil around this bearing and maintaining it effectively lubricated. This pumping action keeps the oil from working out of the bearing, the passage 29 being made smaller than the discharge capacity of the ridge 27 acting as a pump at the normal running speed. When the shaft 17 stops, this pumping action, of course, also ceases, but with the parts stationary, the oil does not leak out appreciably. When the shaft 17 is stationary the oil readily works around the ridge 27 and primes the pump, so to speak. The stuffing box construction illustrated merely constitutes an additional protection against oil leakage, principally to prevent any gradual escape of oil while the shaft 17 is stationary, and when the parts are somewhat worn or improperly fitted; and in practice, this stuffing box may be omitted, if desired.

Obviously, various modifications and adaptations may be made in the particular construction shown and described without departing from its functions and principles

of operation, and I desire to have it understood that this construction is merely one 55 illustrative embodiment of my invention.

What I claim as new and desire to secure by Letters Patent of the United States, is:—

1. A leak-proof bearing structure for the high speed worm shafts of worm gearing 60 which is enclosed in a housing filled with lubricant, comprising a stationary bearing sleeve for the worm shaft, said sleeve being formed with a cylindrical open-ended casing at the inner end, and means constituting a 65 spirally wound ridge rotating with the shaft and fitting closely within said casing, said ridge being pitched opposite to the worm on said shaft and acting while the shaft rotates to force lubricant inward from the 70 bearing sleeve.

2. A bearing structure for high speed shafts adapted to prevent leakage of lubricant, comprising a stationary bearing sleeve in which the shaft rotates, said sleeve being 75 formed at its inner end with a cylindrical casing having an open end, a collar fixed to the shaft and provided with a spirally wound ridge fitting closely within said casing, said ridge being pitched and co-operating 80 with said casing while the shaft is rotating at high speed to force lubricant inwardly from the bearing sleeve.

3. A bearing structure for high speed shafts comprising, in combination with a 85 bearing sleeve, a cylindrical casing at the inner end of said sleeve, a spirally wound ridge within the casing, and rotating with the shaft, and means permitting circulation of oil from one end of the casing to the 90 other through the bearing sleeve.

4. A device for preventing leakage of lubricant out of the bearings of high speed shafts projecting from housings filled with lubricant, comprising an open-ended cylindrical casing and a duplex worm driven by the shaft and fitting tightly in the casing, said worm and casing constituting a pump to force lubricant inward from the shaft bearing.

5. A device of the character described comprising, in combination with a high speed shaft and a bearing sleeve therefor, means driven by the shaft for forcing oil in one direction between the shaft and sleeve. 105

MAURICE F. GEER.
